CLAIM

The ornamental design for a cup with a spritzing mechanism, as shown and described.

DESCRIPTION

FIG. 1 is a perspective view of the first embodiment my new design for a cup with a spritzer mechanism, with both the inner and outer cup walls being transparent;

FIG. 2 is a front elevation view of my new design for the cup with a spritzing mechanism of FIG. 1;

FIG. 3 is a rear elevation view of my new design for the cup with a spritzing mechanism of FIG. 1;

FIG. 4 is a side elevation view of my new design for the cup with a spritzing mechanism of FIG. 1, the opposite side being a mirror image;

FIG. 5 is a top view of the cup with a spritzing mechanism of FIG. 1.

FIG. 6 is a bottom view of the cup with a spritzing mechanism of FIG. 1;

FIG. 7 is a perspective view of the second embodiment of the cup with a spritzing mechanism of FIG. 1, the broken lines showing portions of the design which form no part of the claim;

FIG. 8 is perspective view a third embodiment of the cup with spritzing mechanism of FIG. 1 with this embodiment having an opaque inner cup, the broken lines showing portions of the design which form no part of the claim;

FIG. 9 is a front elevation view of my new design for the cup with a spritzing mechanism of FIG. 1;

FIG. 10 is a rear elevation view of my new design for the cup with a spritzing mechanism of FIG. 1; and,

FIG. 11 is a side elevation view of my new design for the cup with spritzing mechanism of FIG. 1, the opposite side being a mirror image.
